(57) **CLAIM**

The ornamental design for a CT scanning appliance for implant dentistry, as shown and described.

DESCRIPTION

FIG. 1 is a front view of the CT scanning appliance for implant dentistry showing my new design,

FIG. 2 is a rear view thereof,

FIG. 3 is a right side view thereof,

FIG. 4 is a left side view thereof,

FIG. 5 is a top view thereof,

FIG. 6 is a bottom view thereof,

FIG. 7 is a perspective side view thereof; and,

FIG. 8 is a front view of the CT scanning appliance containing bite registration material seated to the upper arch of an individual, the bite registration material and arches of the individual shown in phantom comprising no part of the present invention.
